UTILITY CART

Karl O. Larson, St. Paul, Minn.

Application August 26, 1957, Serial No. 47,506

Term of patent 7 years

(Cl. D14—3)

Figure 1 is a side elevational view of a utility cart showing my new design.

Figure 2 is a front end view thereof.

Figure 3 is a top plan view thereof.

Figure 4 is a rear end view thereof.

Figure 5 is a side view of the wheel and support therefor looking at the same from the inside.

I claim:

The ornamental design for a utility cart, as shown.
